UNITED STATES PATENT OFFICE.

ARTHUR W. HELMHOLTZ, OF HARRISBURG, ILLINOIS.

DESIGN FOR AN ELECTRIC LANTERN.

Application filed April 25, 1924. Serial No. 9,403. Term of patent 14 years.

To all whom it may concern:

Be it known that I, ARTHUR W. HELMHOLTZ, a citizen of the United States, residing at Harrisburg, in the county of Saline and State of Illinois, have invented a new, original, and ornamental Design for Electric Lanterns, of which the following is a specification, reference being had to the accompanying drawing, forming a part thereof.

In the drawing:

Figure 1 is a front elevational view;
Figure 2 is a side elevational view; and
Figure 3 is a view as seen from below.

I claim:

The ornamental design for an electric lantern as shown.

ARTHUR W. HELMHOLTZ.
